J. PIEPGRAS

SILL AND BOLSTER CLAMP

Filed May 26, 1927

INVENTOR.

J. Piepgras
Watson E. Coleman
ATTORNEY.

UNITED STATES PATENT OFFICE.

JOHN PIEPGRAS, OF PAULLINA, IOWA.

SILL AND BOLSTER CLAMP.

Application filed May 26, 1927. Serial No. 194,428.

This invention relates to devices for attaching hay racks to the bolster of a wagon, and the general object of the invention is to provide a clip or clamp for this purpose which is so designed that it will prevent the hay rack sill from cutting into or through the bolster of the wagon and provide means whereby the load will have a good bearing on the wagon bolster to thus prevent the hay rack sills from breaking and keep the hay rack from sliding off of the wagon or out of place.

My invention is illustrated in the accompanying drawing, wherein:—

15 Figure 1 is a perspective view of my improved sill and bolster clamp;

Figure 2 is a front elevation with the bolster in section;

Referring to the drawing, it will be seen that my clip or clamp comprises the iron plate 10 which has an extension 11 integral therewith, this extended portion having two downwardly extending, opposed walls 12. Welded or otherwise attached to the plate 25 10 are the upright straps 13 which are preferably, though not necessarily, formed with the forwardly extended vertical portions 14 extending down to the channelled seat 11. These upright straps 13 are provided with 30 bolt holes 15 and the extremities of the plate 10 are also formed with bolt holes 16.

The plate 10 with its extension 11 is about four inches wide. The wagon bolster A fits within the seat formed by the parts 35 11 and 12 and is bolted thereto by bolts passing through the uprights 13 and through the extremities of the plate 10 at the apertures 16. The vertical members 13 are bolted onto the sill B and keep the sill from 40 breaking and also reinforce the downwardly extending flanges 12. This prevents these flanges 12 from bending when the hay loader is pulled behind a hay wagon. Preferably also the flanges 12 are formed with apertures 45 17 for the passage of a bolt 19 and the

flanges 13 are provided with bolt holes 18 below the plate or web 10. These bolts will keep the front part of the sill from sliding sidewise or from lifting up. While I do not wish to be limited thereto, these 50 clamps are preferably made of malleable iron and have all the necessary and requisite strength.

This construction is practically unbreakable. It prevents the sill from wearing 55 against the bolster and prevents any breakage of the sill and at the same time holds the frame of the hay loader in firm engagement with the bolster and prevents any relative slipping of these parts. It furthermore 60 prevents undue wear on the bolster and on the sills and keeps every part in its place.

I claim:—

1. A sill and bolster iron comprising a structure including two substantially parallel angle irons, one flange of each being in parallel planes and extending in the same direction, the other flanges being in approximately the same plane with each other but extending in opposite directions, said angle 65 irons being connected at about their mid-length by a flat plate at right angles to their length, said plate extending outward beyond the coplanar flanges.

2. A sill and bolster iron comprising an 75 integral structure having substantially the form of two parallel angle irons, one flange of each being in parallel planes extending in the same direction, the other flanges being coplanar but extending in opposite directions, said angle irons being connected about mid-length by a flat plate disposed 80 in a plane at right angles to the length of the angle irons, said plate extending outward beyond the coplanar flanges, the plate 85 and said angle irons having apertures for attaching bolts.

In testimony whereof I hereunto affix my signature.

JOHN PIEPGRAS.
